VOLATILE FUMIGANT PAD

Fred H. Mayer, Portland, Oreg.

Application February 14, 1947, Serial No. 728,413

2 Claims. (Cl. 299—24)

1

This invention relates to insecticides and deodorizing volatile pads, of the same general description illustrated and described in my Patent No. 2,054,434, dated Sept. 15, 1936, except that by reason of structural changes that will be described hereinafter, the rate of volatilization of the deposits on the fingers of the pad may be selectively varied within quite a wide range, which is stated to be the object of this invention.

In placing many thousands of the pads of the kind shown in the patent, it was discovered that the rate at which the deposits of volatile material volatilize is sharply increased if they are separated from each other by a space of about the width of a finger with its deposit; and that there is a layer of saturated atmosphere that builds up around each surface and effectively prevents access of fresh atmosphere to the surface of volatilizable material except at a slow rate. It has also been proved to my satisfaction that the layer of gaseous atmosphere created by evaporation tends to cling to and remain in contact with the body of material from which it was derived and that a flat pad of deposit built up on a cardboard, whether or not it has partial divisions intended to separate fingers, has a much slower volatilization rate than if actually divided into fingers separated from each other by at least the breadth of a single finger. I take advantage of this discovery by the structure shown in the drawing, in which:

Fig. 1 illustrates a cardboard mounting having six dependent fingers with heavy coats of insecticide material;

Fig. 2 shows the same structure shown in Fig. 1 but with the card folded upon itself to place the side boundaries in juxtaposition and in effect to produce a card with a solid one-piece deposit;

Fig. 3 is a plan view of Fig. 2 from the plane 3—3 in that figure;

Fig. 4 is a somewhat enlarged view of Fig. 2 from the plane 4—4 illustrating what careful tests have shown to be a fact, that a dense layer of saturated air gathers around a group of coated fingers in juxtaposition; and

Fig. 5 shows an enlarged view of two fingers only, taken from the plane 5—5, Fig. 1, illustrating the effect of adequate spacing.

Describing the drawings in greater detail:

Numerals 1 illustrates a cardboard mounting member upon which dependent finger-like parts 2, have been cut. In quantity production, this is always done by a die. Each finger has deposited thereon a deposit 3, of naphthalene or other suitable vaporizable insecticide, the actual composition of which is not a part of this invention. Such cards are commonly hung in closets or laid in chests to repel or destroy moths or their larvae that would otherwise attack any textile of animal fiber that might be stored therein.

In making and selling these insecticide pads, a

considerable reduction in cost can be achieved if the pads are of uniform construction, which brings up the problem that even in a small closet the large pad, such as that shown in Fig. 1, will have a higher rate of volatilization than necessary with a correspondingly shorter life. To remedy this, I have provided the crease 6 in the mounting 1, where the said mounting 1 may be folded backwards upon itself, producing the different insecticide pad shown in Fig. 2, which has a much slower volatilization rate than the same pad had originally.

Though it has not been possible to exactly duplicate conditions for long enough periods to make a closer estimate, the generally slowed up rate of volatilization is thought to closely approximate five eighths of that of a similar pad not folded. In other words, the same pad will last nearly one and six-tenths the time folded as unfolded. If torn apart and the part to be saved is put into a waxed paper sack, a somewhat similar result can be had at the expense of additional care and attention.

In Figs. 4 and 5 the broken lines 7 are intended to illustrate a continuous layer of saturated air in the first instance and the result of spacing in the second.

Having described my invention in what I now believe to be its best form, and explained the principle thereof, what I claim as new and desire to secure by Letters Patent, is:

1. A fumigant pad comprising an elongated cardboard mounting member formed with spaced dependent fingers thereon, said fingers carrying a deposit of vaporizable crystalline material thereon and of such uniform dimensions that when the card is folded upon itself, the fingers will fit spaces to produce a practically unbroken body with materially lower volatilization characteristic than the unfolded card with spaced fingers.

2. An insecticide carrying pad, comprising a foldable mounting member formed with spaced dependent fingers thereon, said fingers carrying independent deposits of volatilizable material thereon of uniform breadth, with spaces therebetween able to accept other fingers therebetween when the said mounting member is folded upon itself, to decrease the number of spaces to slow the rate of volatilization.
